UNITED STATES PATENT OFFICE

120,556

DESIGN FOR A PIPE OR SIMILAR ARTICLE

Louis J. Robertson, New York, N. Y.

Application October 25, 1938, Serial No. 80,670

Term of patent 3½ years

To all whom it may concern:

Be it known that I, Louis J. Robertson, a citizen of the United States and resident of New York, county of New York, State of New York, have invented a new, original, and ornamental Design for a Pipe or Similar Article, of which the following is a specification, reference being had to the accompanying drawing, forming a part thereof.

I claim:

The ornamental design for a pipe or similar article, as shown.

LOUIS J. ROBERTSON.
